N. KOMORI.

CARPET.

No. 17,733.

Patented Sept. 20, 1887.

UNITED STATES PATENT OFFICE.

NORIC KOMORI, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,733, dated September 20, 1887.

Application filed August 16, 1887. Serial No. 247,122. Term of patent 3½ years.

To all whom it may concern:

Be it known that I, NORIC KOMORI, of New York city, in the county and State of New York, have invented a new and original Design 5 for Carpets, of which the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view of a carpet showing my new design.

15 My design comprises a body part, A, and a border, B.

The body part consists of a number of separate sprays or stems, the stem-work in each being more or less irregularly curved and supporting circular flowers or buds and small leaves.

20 The ground is ornamented with a damask-work of a pebbled or grape-like character.

My border has a lower margin or band com-

posed of inconspicuous small circular flowers and leaves lying lengthwise upon one another. 25 The middle portion of the border consists of small stems supporting a flower and several leaves, all arranged on a damask ground of a pebbled or grape-like character. The outer part of the border is composed of a running 30 stem-work supporting circular flowers, above which are large leaves and small flowers interspersed.

What I claim as new, and desire to secure by Letters Patent, is— 35

1. In a design for carpets, the body A, substantially as shown.

2. In a design for carpets, the border B, substantially as shown.

3. The design for carpets, consisting of the 40 body A and border B, substantially as shown.
